[57] CLAIM

The ornamental design for a turtle toy, substantially as shown and described.

DESCRIPTION

FIG. 1 is an oblique view showing portions of the top, front and left-hand side of a turtle toy showing my new design;

FIG. 2 is a side-elevational view of the right-hand side of the toy;

FIG. 3 is a rear-elevational view of the rear of the toy; and

FIG. 4 is a bottom plan view showing the bottom of the toy.

FIG. 1

FIG. 4

FIG. 2

FIG. 3
